Primary Examiner — Paula Greene

(57) CLAIM

The ornamental design for a heart-shaped keepsake, as shown and described.

DESCRIPTION

FIG. 1 is a perspective top view of a heart-shaped keepsake; FIG. 2 is a perspective bottom view of the heart-shaped keepsake;

FIG. 3 is a front elevation view of the heart-shaped keepsake; FIG. 4 is a rear elevation view being a mirror image thereof; FIG. 5 is a left side elevation view of the heart-shaped keepsake, the right side elevation view being a mirror image thereof;

FIG. 6 is a top plan view of the heart-shaped keepsake; and, FIG. 7 is a bottom plan view of the heart-shaped keepsake. The broken lines shown in FIG. 2 and FIG. 7 are for illustrative purposes only and form no part of the claimed design.
